(57) CLAIM

The ornamental design for a brush with handle and flat surface, as shown and described.

DESCRIPTION

The claimed brush with handle and flat surface is used for cleaning shoes and clothing.

FIG. 1 is a top plan view of a brush with handle and flat surface showing my new design;

FIG. 2 is a front elevational view thereof, the rear being a mirror image;

FIG. 3 is a left side elevational view thereof; the right side being a mirror image; and,

FIG. 4 is a perspective view thereof.
